UNITED STATES PATENT OFFICE

93,497

DESIGN FOR A CABINET FOR A MECHANICAL GAME AND VENDING APPARATUS OR SIMILAR ARTICLE

Jerry F. Macourek, Columbus, Ohio, assignor to Gustavus W. Snyder, Columbus, Ohio

Application June 27, 1934, Serial No. 52,360

Term of patent 7 years

To all whom it may concern:

Be it known that I, JERRY F. MACOUREK, a citizen of the United States, residing at Columbus, in the county of Franklin and State of Ohio, have invented a new, original, and ornamental Design for a Cabinet for a Mechanical Game and Vending Apparatus or Similar Article, of which the following is a specification, reference being had to the accompanying drawing, forming a part thereof.

Fig. 1 is a perspective view of a cabinet for a mechanical game and vending apparatus or similar article, showing my new design;

Fig. 2 is a side elevation thereof.

I claim:

The ornamental design for a cabinet for a mechanical game and vending apparatus or similar article, as shown.

JERRY F. MACOUREK.
